UNITED STATES PATENT OFFICE

WILLIAM H. CONKLIN, OF ANSONIA, CONNECTICUT

DEVICE FOR TRANSMITTING INTELLIGENCE

Application filed August 17, 1929. Serial No. 386,599.

This invention relates to a device for transmitting intelligence, such for example as transmitting messages between ships, or it may be used by the deaf and dumb in conversation, and has for an object to provide a device for this purpose which is simple in construction, may be easily operated and as easily read at a distance, and is easily portable.

It is also an object of the invention to provide a device of this character in which any message desired may be easily and quickly transmitted.

With the foregoing and other objects in view, the invention consists in certain novel features of construction, combinations and arrangements of elements as will be more fully disclosed in connection with the accompanying drawing.

In this drawing:

20 Fig. 1 is a partial side elevation and a partial longitudinal section through a device embodying my invention.

Fig. 2 is a front elevation thereof.

25 Fig. 3 is a diagrammatical view giving samples of the different signals that may be transmitted.

Fig. 4 is a wiring diagram of the device.

Fig. 5 is a detail section showing one construction by which the lamps may be mounted.

30 Fig. 6 is a diagrammatic view showing how the system may be extended to increase the number of two-light combinations that may be formed.

35 Fig. 7 shows an example of an alphabet which may be used with this device.

Figs. 8 and 9 show how the device may be employed at an aviation field for transmitting any message desired from the ground to the occupants of an air plane or from the plane to the person on the ground.

The device illustrated comprises a box 10 having a front wall 11 and a removable back wall 12 to permit access to the interior of the box. If the device is to be used on ships, this box should be water tight to keep moisture out of the various electrical connections. The front wall 11 is provided with openings 13 behind which are mounted electric lamps 14, these lamps being arranged with respect to

each other as indicated in Fig. 2. For ordinary use six lamps are sufficient, arranged in three pairs with the lamps also in two parallel rows as indicated, and the openings in the front plate 11 preferably hold colored lenses or bull's eyes 15. Between the central pair of lamps 40 and 43 there is a guide lamp having a lens 16 of different color from the lenses 15, the plate 11 having an opening for this lens with a lamp behind it the same as behind the lenses 15. The colors of the lenses are immaterial so long as the lens 16 is different from the lenses 15 so that they can be distinguished. For example, it has been found very satisfactory to make the guide light or lens 16 green and the lenses 15 red.

As a convenient manner of mounting, a metal panel 17 may be mounted in the box back of the front wall 11, and this panel may have threaded openings to receive the threaded necks 18 of sheet metal curved reflectors 19, forming a socket to receive these lamps 20 having the usual screw shell contacts 21 to thread into the socket. It will, of course, be understood that any other suitable type of socket may be used if desired. The reflectors 19 embrace the lenses 15 and 16 at their forward ends so that the light from any individual lamp is transmitted through one lens only. The central lamp contact 22 may engage a spring contact 23 carried by an insulated plate 24 or plate of insulating material mounted on the back of the panel 17 by any suitable means such as the studs 25. A binding post screw 26 may be used to secure contact 23 to the insulating plate 24 and also form a connection by means of which a lead 27 from a control switch may be connected. Also mounted in the box may be a battery 28, one pole of which may be connected by a lead 29 to the panel 17. As the lamp sockets are grounded on this panel, one contact of each lamp is thus electrically connected with one terminal of the battery. The other terminal of the battery leads through a flexible cable 30 to a plurality of control switches which are preferably mounted in a portable box or other suitable support 31. These switches are indicated by push-buttons 32, 33, 34, 35, 36 and 37, there being one switch for each of the

lights 14 behind the bull's eyes 15. For convenience in operating these switches they are arranged in the same relative positions to each other as are the flash lamps which they control, there being a lead from each switch through the cable 30 to its corresponding lamp. Thus there is a lead 38 from the switch 35 to the upper right hand lamp indicated at 42, Fig. 2. The lamps 39 to 44 are each connected by a similar lead to their respective control switches 32 to 37. Thus by pushing any of the buttons, 32 to 37 any single lamp 39 to 44 or any combination thereof with one or more of the other lamps may be flashed. When the device is used at night the guide lamp 16 is lighted continuously and it is therefore controlled by a snap switch 45 so that it is not flashed but lighted continuously.

Altho in the drawing, the lamps themselves are flashed by the switches, it will, of course, be understood that shutters in front or behind the lenses 15 may be operated instead. As the switches 32 to 37 are arranged in the same order and relative arrangement as are flash lights 39 to 44, respectively, it is a very simple matter for the operator to operate the buttons and switches to flash any individual lamp desired, or any combination of this lamp with any of the other lamps. A few of the signals and combinations which may be transmitted are illustrated in Fig. 3, that is, the first one represents the lamp 42, or the upper right hand lamp lighted in connection with the guide lamp 16. The second one represents this lamp 42 and the left hand lamp 40 of the middle pair lighted in connection with the guide lamp. Other combinations are shown in the remainder of Fig. 3 and the rest will be readily apparent. It will be obvious that these arrangements and combinations can be easily read and distinguished at any distance at which the panel is visible. It may of course be used either in the upright position shown or may be used in the horizontal position and be as easily read. Each lamp 39 to 44 when flashed either alone or in combination with the other lamps may be used to transmit a certain letter or a certain word value according to a rule. If the device is used in daylight or by people close together as where two deaf and dumb people use it for conversing, the use of the guide lamp 16 will be unnecessary as the arrangement of the lamps 39 to 44 is easily discernible. At night, however, the guide lamp 16 clearly distinguishes between the lamps 39 to 44 by their relative arrangement with respect to the guide lamp.

The six lamps shown provide a sufficient number of different signals for transmitting any message desired. If, however, it is found desirable to be able to transmit a larger number of different combinations involving the use of two flash lights only, this could be done

by adding additional pairs of lights and additional guide lights between the intermediate pairs as indicated in Fig. 6. Thus there could be an additional pair of lights 46 and 47 with an additional guide light 48 between the pair of lights 39 and 42. This arrangement is, however, not necessary and the six signal lamps and the one guide lamp give a sufficient number of different signals to transmit any message desired, as of course, combinations using more than two flash lights can be used. Fig. 6, however, is shown merely to indicate how the system may be extended to increase the number of signals which can be given by the use of two flash lights only beside the guide light or lights.

It will be apparent from the foregoing description that as lights 39 to 44 are of a different color from the guide light 16, they are easily identified even at night as their relative positions with respect to each other is indicated by the guide lamp. The signals may be transmitted just as rapidly as the operator can manipulate the buttons or switches 32 to 37 to flash the various lamps or combinations thereof as desired to transmit the desired message.

In Fig. 7 I have illustrated by way of example an alphabet which may be used with this device for transmitting any message desired. This is merely an example as, of course, various signals may be used for different letters as desired, but the alphabet illustrated is very simple and easily learned. The line 52 indicates the letters corresponding to the signals under each letter. The red lights 39 to 44 are indicated by the circles while the green pilot light 16 is indicated by the diamond shaped figure, it being necessary only that this light be different so as to be distinguishable from the other lights. In learning the alphabet, the light 39 is considered as No. 1, light 40 as No. 2, light 41 as No. 3, light 42 as No. 4, light 43 as No. 5 and light 44 as No. 6. These correspond with the numbers in the lines indicated at 51. It will be seen that in making up this particular alphabet the lights are taken in regular order making it much easier to memorize. The cabled line 53 in certain signals means the particular signal is flashed twice in quick succession for that letter.

In Figs. 8 and 9 is illustrated one of the many uses of this device. Thus, the lights 39 to 44 with the pilot light 16 may be mounted on a tower 49 or any other similar support, or even placed on the ground, and any message desired may be transmitted easily and rapidly to the occupants of a plane 50. Thus, for instance, should one of the landing wheels be lost off the plane this fact can be easily and quickly transmitted to the pilot and he can control his plane accordingly when landing. Similarly the lights can be installed on the plane as illustrated in Fig. 120

9 and used by any one in the plane for sending messages to the ground or another ship.

Having thus described my invention, what is claimed is:

1. In a communicating device, three pairs of lights arranged in two parallel rows, a guide light of a different color arranged between the central pair of lights, and control means for said lights including an individual manually operable control switch for each of the first mentioned lights, said control switches being arranged in the same relative positions to each other as are the corresponding lights.
2. In a communication device, three pairs of lights arranged in two parallel rows, and control means for said lights including an individual manually operable control switch for each of the first mentioned lights, said control switches being arranged in the same relative positions to each other as are the corresponding lights.
3. In a communicating device, three pairs of similar lights arranged in two parallel rows, a guide light of a different appearance from the other lights arranged between the central pair of lights, and control means for said first mentioned lights including an individual manually operable control switch for each of these lights, said control switches being arranged in the same relative positions to each other as are the corresponding lights.

In testimony whereof I affix my signature.
WILLIAM H. CONKLIN.
